(57) **CLAIM**

The ornamental design for a pour spout, as shown and described.

DESCRIPTION

FIG. 1 is front elevational view of the pour spout of the claimed design;

FIG. 2 is rear elevational view of the pour spout of the claimed design;

FIG. 3 is an elevational view of the left side of the design as seen in FIGS. 1 & 2;

FIG. 4 is an elevational view of the right side of the design as seen in FIGS. 1 & 2;

FIG. 5 is a perspective view of the design as seen looking from above and toward the front right as seen in FIG. 1;

FIG. 6 is a perspective view of the design as seen looking from below and toward the rear right as seen in FIG. 1;

FIG. 7 is a perspective view of the design as seen looking from above with the stopper removed for clarity of disclosure; and,

FIG. 8 is a schematic exploded cross-sectional view.
